CLAIM

The ornamental design for an x-ray film re-screening apparatus, as shown and described.

DESCRIPTION

FIG. 1 is a perspective view of the x-ray film re-screening apparatus showing the front and right side;

FIG. 2 is a front elevation view of the apparatus shown in FIG. 1;

FIG. 3 is a rear elevation view of the apparatus shown in FIG. 1;

FIG. 4 is a side elevation view, depicting the left side of the apparatus shown in FIG. 1;

FIG. 5 is a side elevation view, depicting the right side of the apparatus shown in FIG. 1; and,

FIG. 6 is a top plan view of the apparatus shown in FIG. 1. The bottom is plain and unornamented.
